CLAIM

The ornamental design for a multi-function socket, as shown and described.

DESCRIPTION

FIG. 1 is a top, front perspective view of a multi-function socket, showing our new design in a closed configuration; FIG. 2 is a bottom, rear perspective view of the multi-function socket of FIG. 1;

FIG. 3 is a top view of the multi-function socket of FIG. 1; FIG. 4 is bottom view of the multi-function socket of FIG. 1;

FIG. 5 is a rear view of the multi-function socket of FIG. 1; FIG. 6 is a front view of the multi-function socket of FIG. 1;

FIG. 7 is a right side view of the multi-function socket of FIG. 1;

FIG. 8 is a left side view of the multi-function socket of FIG. 1;

FIG. 9 is a top, front perspective view of a multi-function socket, showing our new design in an open configuration; FIG. 10 is a bottom, rear perspective view of the multi-function socket of FIG. 9;

FIG. 11 is a top view of the multi-function socket of FIG. 9; FIG. 12 is a bottom view of the multi-function socket of FIG. 9;

FIG. 13 is a rear view of the multi-function socket of FIG. 9;

FIG. 14 is a front view of the multi-function socket of FIG. 9;

FIG. 15 is a right side view of the multi-function socket of FIG. 9; and,

FIG. 16 is a left side view of the multi-function socket of FIG. 9.

(Continued)

The broken lines in the drawings are for the purpose of illustrating portions of the multi-function socket that form no part of the claimed design.
